UNITED STATES PATENT OFFICE.

JOSEPH KAUFMANN, OF CHICAGO, ILLINOIS.

IMPROVEMENT IN COMBINED HAT-HOOKS, NAIL-FILES, WATCH-KEYS, AND TOOTH-PICKS.

Specification forming part of Letters Patent No. **173,645**, dated February 15, 1876; application filed July 22, 1875.

To all whom it may concern:

Be it known that I, JOSEPH KAUFMANN, of Chicago, in the county of Cook and State of Illinois, have invented a new and useful Combined Hat-Hook, Nail-File, Watch-Key, and Tooth-Pick, of which the following is a specification:

The nature of my invention consists in combining, in a neat and simple pocket-tool, a hat-hook, nail-file, watch-key, and tooth-pick, as more fully hereinafter set forth.

Figure 1 is a perspective view of the device as most conveniently arranged to carry in the pocket, and also presenting the watch-key ready for use. Fig. 2 shows the arrangement of the tooth-pick. Fig. 3 shows, in perspective, its application as a hat-hook.

In the drawing, A represents a tweezer made from a single strip of metal bent upon itself, with a clasp, a, sliding upon it between the jaws and the heels. When slid out toward the jaws the clasp a brings the latter forcibly together, and secures them to a hat-rim or anything interposed between them. B is a hook pivoted in the bend of the tweezer by a rivet, the bend being slotted in the middle to allow the hook to revolve on the rivet. To the heel of the hook is secured the pipe b

of a watch-key. One face of the tweezer is file-cut, as at c, Fig. 2, for trimming fingernails. d is a tooth-pick, pivoted at one end to the heel-rivet, so as to lie along one edge of the tweezer when swung over it. The clasp a slides over it, and keeps it in position until required, when the latter is run off it at the point. When the clasp is so moved up, it serves as a clamp to compress the jaws of the tweezer, while, at the same time, the hook is freed, and may be engaged with a cord or any object that will hold it, either by hanging it over, or pressing the point of the hook into, said object. Ordinarily the point of the hook is received in a slot in the plain side of the tweezer, the clasp having been previously run back and hooked there by sliding the clasp up over the point of the hook.

What I claim as my invention is—

In combination with the tweezers having one of its sides file-cut, the hook and watch-key, tooth-pick, and sliding clasp, substantially as described.

JOSEPH KAUFMANN.
